UNITED STATES PATENT OFFICE.

WILLIAM L. WALLACE, OF DAVIDSON, NORTH CAROLINA.

ATTACHMENT FOR CIGARETTE-HOLDERS.

1,384,813.

Specification of Letters Patent. Patented July 19, 1921.

Application filed July 17, 1919. Serial No. 311,416.

To all whom it may concern:

Be it known that I, WILLIAM L. WALLACE, a citizen of the United States, and a resident of Davidson, in the county of Mecklenburg 5 and State of North Carolina, have made certain new and useful Improvements in Attachments for Cigarette-Holders, of which the following is a specification.

My invention relates to cigarette holders.

10 An object of my invention is the provision of an attachment for a cigarette holder by means of which a cigarette even when burned up to the holder, may be ejected without difficulty or inconvenience and securely held 15 within the holder against accidental displacement until it is desired to eject it.

I will describe one form of cigarette holder, and one form of attachment embodying my invention.

20 In the accompanying drawings:

Figure 1 is a perspective view showing one form of cigarette holder, having applied thereto one form of attachment embodying my invention.

25 Fig. 2 is a view showing in side elevation and partly in section, the holder and attachment shown in Fig. 1.

Fig. 3 is a plan view of the attachment detached from the holder, and,

30 Fig. 4 is a similar view showing the attachment in end elevation.

Similar reference characters refer to similar parts in each of the several views.

Referring specifically to the drawing, and 35 particularly to Figs. 1 and 2, H designates a conventional form of cigarette holder which comprises in the present instance, an octagonal shaped body portion 10 formed with a tapered stem portion 12 terminating in a bit or mouth piece 13, and a tapered cigarette receiving socket 14 that communicates with the usual bore 15 extending through the stem, as shown in Fig. 2.

40 My attachment is designated generally at A, and as shown in Figs. 3 and 4, comprises a T-shaped piece of resilient metal, a portion of which is bent to provide a split band 16, while the remaining portion is bent upon itself as at 17 to provide a clip 18.

45 As shown to advantage in Fig. 2, the free end of the clip 18 is bent at right angles to provide a lip 19, while in advance of the lip, the metal is outstruck to provide a retaining lug 20.

50 When the attachment A is applied to the cigarette holder as shown in Figs. 1 and 2,

the clip 18 embraces the holder in such manner that the lug 20 and lip 19 are disposed within the socket 14. The band 16 partially encircles the octagonal body portion 10, and is preferably bent to a corresponding shape so as to prevent its rotation about the holder and to lock the lip 19 in position.

When a cigarette is inserted within the 60 socket 14 the inner end of the cigarette abuts the lip 19, while the lug 20 embeds itself within the cigarette and thus prevents accidental displacement of the same. The lug 20 has been found to be especially useful to maintain the cigarette within the holder 70 when flicking the ashes from the cigarette, as this latter operation generally causes the cigarette to fall out in the holder of the ordinary construction.

When it is desired to eject from the holder, 75 the short end or stub of a cigarette, it is only necessary to slide the band 16 forwardly on the holder, thus causing the lip 19 to move outwardly of the socket 14 and thereby pushing the cigarette from the socket.

To prevent the attachment from falling off of the holder during the ejecting operation, I form one face of the body 10 with a shoulder 21 which is disposed to limit the outward movement of the attachment by engaging a shoulder 22 formed on the inner edge of the band 16, as clearly shown in Figs. 2 and 4. When the attachment is moved forward to eject the cigarette, the shoulder 22 strikes the shoulder 21 before the clip 18 can be disengaged from the holder, so that the entire attachment remains in operative position upon the holder to be returned to its normal position.

From the foregoing description taken in 95 conjunction with the accompanying drawings, it will be manifest that I have provided a simple and efficient attachment for ejecting a cigarette from the holder when desired and for retaining it within the holder 100 until it is desired to eject it, which attachment may be easily fitted to the various shapes of holders without necessitating any material change in the construction thereof, and an attachment which upon being applied to a holder forms an integral part 105 thereof and cannot be accidentally displaced.

Although I have herein shown and described only one form of cigarette holder, and one form of attachment embodying my 110 invention, it is understood that various changes and modifications may be made

herein without departing from the spirit of the invention and the spirit and scope of the appended claims.

Having described my invention, what I claim is:—

1. In combination, a cigarette holder, having a shoulder formed thereon, an attachment comprising a band embracing the holder, a clip formed integrally with and arranged at right angles to the band and adapted to embrace the inner and outer walls of the socket of the holder, a lip on the inner end of the clip and disposed within the socket, a lug on the clip in advance of
- 10

the lip and disposed within the socket, and a shoulder on the band and adapted to engage the shoulder on the holder.

2. An attachment for cigarette holders comprising, a clip adapted to engage the walls of a socket in the cigarette holder, a lip formed on the clip and disposed within the socket, a lug in advance of the lip and disposed within the socket, a split band connected to said clip, and a shoulder formed on one edge of the band for the purpose described.
